UNITED STATES PATENT OFFICE.

JAMES BRUCE, OF CAPELTON, CANADA.

DESIGN FOR A TOY.

SPECIFICATION forming part of Design No. 26,425, dated December 22, 1896.

Application filed November 10, 1896. Serial No. 611,680. Term of patent 7 years.

To all whom it may concern:

Be it known that I, JAMES BRUCE, a subject of the Queen of England, residing at Capelton, in the Province of Quebec and Dominion of Canada, have invented and produced a certain new and original Design for Toys; and I do declare the following to be a full, clear, and exact description of the invention, such as will enable others skilled in the art to which it appertains to make and use the same.

My invention relates to a new and original design for a toy. It relates to the entire configuration of the toy.

My invention relates particularly to a toy as illustrated in the accompanying drawing, in which the figure is a perspective view of a toy embodying my design.

The leading features of my design appear in the following description.

1 is the circular base, having a projecting flange 2. The body 3 tapers upwardly in the shape of the frustum of a cone, the plane top of which is formed with a semicircular recess 4. The tapering sides of the frustum are formed with a series of flutes or semicircular channels or grooves 5, as shown in the drawing.

Having thus described my design for a toy, what I claim as new, and desire to secure by Letters Patent of the United States, is—

The design for a toy, substantially as herein shown and described.

In testimony whereof I hereunto affix my signature in presence of two witnesses.

JAMES BRUCE.

Witnesses:

ACHILLE BRUNELLE,
THOMAS COTTON.
